(57) **CLAIM**

I claim the ornamental design for a gift wrap work station,
as shown and described.

DESCRIPTION

FIG. 1 is an isometrical view of the gift wrap work station
generally showing the top right side features;

FIG. 2 is an isometrical view generally showing the top left
side features;

FIG. 3 is an isometrical view generally showing the front,
and bottom features;

FIG. 4 is a top view thereof;

FIG. 5 is a bottom view thereof;

FIG. 6 is a rear end view thereof;

FIG. 7 is a front end view thereof;

FIG. 8 is a left side view thereof; and,

FIG. 9 is a right side view thereof.
